UNITED STATES PATENT OFFICE.

WILLIAM McNAMARA, OF CLEVELAND, OHIO.

HYDRANT.

SPECIFICATION forming part of Letters Patent No. 269,440, dated December 19, 1882.

Application filed June 24, 1882. (No model.)

To all whom it may concern:

Be it known that I, WILLIAM McNAMARA, of Cleveland, in the county of Cuyahoga and State of Ohio, have invented new and useful 5 Improvements in Hydrants, of which the following is a description of the construction and operation thereof, reference being had to the annexed drawings, making a part of this specification, in which—

10 Figure 1 shows an external side view of the machine. Fig. 2 is a transverse longitudinal section. Figs. 3, 4, and 5 are detached sections. Like letters of reference denote like parts in the several views.

15 The lower part or section of the hydrant consists of a tubular shell, A, having on each of two opposite sides a conduit, B and C, respectively, which are in open communication with the shell at *a* and *b*, Fig. 2. In said shell 20 is fitted, in a water-tight manner, a tubular core, D, a detached longitudinal section of which is shown in Fig. 3. Said core is made water-tight in the shell by means of packing *c*. Between said packing the surface of the 25 core is cut away, forming an annular recess, *e*, Fig. 3. A similar recess is made in the core at *f*. Said recesses, when the core is in the shell, form, with the sides thereof, annular chambers *a'* and *b'*, the purpose of which will presently 30 be shown. Within the core is movably fitted a hollow valve-stem, E, made water-tight therein by means of packing *e'*. To the lower end of the stem is secured a valve, F, having its seat in the lower end of the shell A, for opening and closing the water-passage G. To the 35 said valve-stem is secured a rod, H, passing through the tube or dry-pipe I, the lower end of which pipe is screwed into the core, as seen at J, Fig. 2. To the above-described lower 40 section of the hydrant is screwed a pipe, K, inclosing the tube I. The opposite end of the pipe is secured to the upper end of the hydrant, consisting of a shell, A', provided with a discharging-nozzle, B'. In said shell A' is 45 a cylinder, C', to the bottom of which is screwed the upper end of the tube I, thereby connecting the core D of the lower section of the hydrant with the cylinder C', as seen in the drawings. In said cylinder is fitted, so as to slide 50 therein, a block, D'. On two sides of the block are ribs *m*, adapted respectively to fit and slide in the slots *n*, made in the sides of the

cylinder. A detached view of the cylinder is seen in Fig. 4, showing one of the slots. Fig. 5 is an end view of the cylinder and block. 55 The purpose of the said ribs is to prevent the block from turning in the cylinder, but at the same time permit it to move up and down therein. The block is operated by a screw, E', attached thereto by a flanged head, N, loosely 60 fitted in the block, and which is prevented from being pulled out therefrom by the flange of the head, adapted to engage a corresponding annular shoulder formed in the block, thereby making a swivel-connection of the 65 screw and head, substantially as seen in Fig. 2. The screw is retained in the block by a nut, *i*, screwed therein, and to which nut the valve-rod H is attached, thereby connecting the screw E', by means of the rod, to the valve 70 F for operating it. The thread of the screw E' is a coarse one and works in a nut, F', screwed into the shell A', as seen in Fig. 2.

The core D, above alluded to, is made up in sections 1, 2, 3, and 4, as seen in Fig. 3, for the 75 convenience of providing the core with packing. It will be observed that the several sections are connected to each other by screw-joints, and that between the collars of the sections the packing is secured. 80

I do not confine myself to the construction of the core as above described, as it may be otherwise made or modified without departing from its general structure.

The practical operation of the hydrant is as 85 follows: The lower section of the machine is set down in the ground as low as the water-main, and is attached thereto by the pipe O in the usual way. As in ordinary hydrants, the upper section is near the surface of the ground. 90 To this end the pipe K, &c., may be longer or shorter, as the setting of the hydrant may require. As shown in the drawings, the valve F is screwed down upon its seat, thereby shutting off the water from the hydrant. Now, 95 on turning the screw E' in the proper direction the block D' is drawn upward in the cylinder C', and with it the connecting-rod H, which, as a consequence, will lift the valve F from its seat and allow the water to flow from 100 the pipe O into the conduits B C, which passes upward therein and out of the openings *b b* into the pipe K, up which it passes to the discharging-nozzle B'. The passage of the water is in-

dicated by the arrows. On turning down the screw E' the valve closes, shutting off the water from the hydrant. That which may be left in the pipe K and the conduits flows therefrom through the waste-hole n' into the hollow stem E of the valve, up which it passes to the vent-hole i, and is discharged therefrom into the annular chamber a', from thence to the outside of the hydrant, through the hole i', Fig. 1, in the side of the shell, thus leaving the hydrant free of water.

It will be obvious from the above that water cannot lodge in the pipe K when shut off from entering the hydrant; nor can it find its way into the dry-pipe I to the valve-rod H, the water being excluded therefrom by the close water-tight joints and packing. Hence the rod H is always kept dry, so that it will work easily, and not be liable to freeze up; nor can the water find its way above the discharging-nozzle, as the packing r at the lower end of the cylinder closes the passage-way about the pipe I, screwed into the cylinder, said cylinder being screwed down upon its bearings in section A' by the screw-nut F', making the whole connection water-tight.

In operating the hydrant the core remains stationary, the valve only being the part moved for opening and closing the hydrant. Hence there is but little frictional wearing of the parts in working the hydrant, which may be used either with or without a stock. Should water leak from the pipe K around the upper end of the core, it can go no farther than to the annular chamber b', Fig. 2, and will run therefrom to the outside through the waste-hole f' in the side of the core and a corresponding hole in the side of the shell, as seen at f' in Fig. 1.

In the drawings the waste-holes are shown as being both on the same side of the shell.

It is preferred to have one on each side, instead of both on one side.

What I claim as my invention, and desire to secure by Letters Patent, is—

1. In hydrants, in combination with the shell A and side conduits in open communication with said shell, the tubular core provided with exterior rings of packing and exterior annular recesses, forming, with the sides of the shell, 50 annular chambers having waste-openings, substantially as described, and for the purpose set forth.

2. In hydrants, the core D, provided with internal packing-rings, e, and annular recesses, 55 in combination with the tubular valve-stem and valve, and shell A', having an outlet, B', substantially as described, and for the purposes set forth.

3. In combination with the tubular core, 60 valve-stem E, and shell, the valve-rod H, pipe I, inclosing said rod, water-pipe K, connecting the shell A and shell A', in the manner substantially as and for the purpose specified.

4. In combination with the pipe I and valve-rod, the slotted cylinder, screw-stem E', loosely connected to the block D', shell A', and screw-nut, substantially as described, and for the purpose set forth.

5. The core D, consisting of sections connected to each other by screw-joints, and having interior and exterior packing and interior and exterior recesses, provided with waste-holes, in combination with the shell A and valve-stem, as and for the purpose specified. 75

In testimony whereof I affix my signature in presence of two witnesses.

WILLIAM McNAMARA.
